OILING DEVICE

Filed July 6, 1922

FIG. 1

FIG. 2

FIG.3

FIG. 4.

INVENTOR
O. Duchatelet
BY E. J. Parker & Son, Attorneys.

UNITED STATES PATENT OFFICE.

OVIDE DUCHATELET, OF MONTREAL, QUEBEC, CANADA.

OILING DEVICE.

Application filed July 6, 1922. Serial No. 573,160.

To all whom it may concern:

Be it known that I, OVIDE DUCHATELET, a subject of the King of Great Britain, and residing at the city of Montreal, in the Province of Quebec, in the Dominion of Canada, have invented a new and useful Oiling Device, of which the following is the specification.

The invention relates to oiling device as described in the present specification and illustrated in the accompanying drawings that form part of the same.

The invention consists essentially of the novel features of construction pointed out broadly and specifically in the claim for novelty following a description in detail of the preferred form of the invention.

The objects of the invention are to oil the bearings in inaccessible places such as the bearings of shaft hangers in machine shops and highly positioned bearings in engine rooms and other places; to eliminate the dangers incident to the oiling of bearings amongst many turning members and belting; and generally to provide a simple and efficient oiler for bearings ordinarily out of reach.

In the drawings, Figure 1 is a side elevation of the oiler shown in the position it is made to assume during the act of oiling.

Figure 2 is a rear view of the oil can.

Figure 3 is a detail of the extensible rod.

Figure 4 is a detail of the funnel adapted to receive the beak of the oil can.

Like numerals of reference indicate corresponding parts in the various figures.

Referring to the drawings, the can 1 is of ordinary construction and need not have any peculiarity to be adapted to this invention.

In place of the usual bail the fork 2 is attached to the ears 3 by means of pivot pins 4 and the can may be removed and replaced with ease.

The fork 2 is offset from the cap 5 which surmounts the extension rod 6. The rod 6 is slidably arranged in the handle 7 which has a converging socket end 8 riveted on to the upper end of the tubular handle. The rod is held in its extended position by the thumb screw 9 and carries adjacent to the upper

end a spring horn 10 projecting from the fixed band 11 and adapted to space the beak 12 of the can to reach the oiling funnel 13 with which the can is closely associated in oiling the bearings 14.

The funnel 13 is made with a slightly tapered neck which fits into the bearing orifice and the dished cover 15 encircling the inlet 16 the latter having an inner flange 17 to receive and guide the beak 12 in oiling operations.

The funnel 13 though part of the oiling device is preferably left in the oil passage to the bearing and where the bearing member revolves the oil will remain in its receptacle until used up by the bearing and will not splash, thereby economizing in oil and considerably reducing the labor in oiling.

The cord 18 is attached to the eye band 19 encircling the beak 12 and passes through the eyes 20 and is fastened to the cleat 21 secured to the handle 7, so that with one hand the can may be upset for oiling purposes.

The can is brought back by the spring 22 from prong to prong of the fork 2 and stretched around the body of the can.

In operation the rod is extended to the height desired and the beak of the can or mouth inserted in the bearing receptacle shown as a can co-operating with the beak in guiding the flow to the bearing orifice.

The spring horn comes in contact with the bearing casting and the can is pushed in against the spring pressure sufficiently to place the beak in the funnel passage and thus direct the oil to the bearing orifice as well as leaving a supply within the funnel.

What I claim is:

An extensible rod having a rearwardly offset pivot bearing and an oil can pivoted therein and a spring member projecting laterally and upwardly from said rod and terminating adjacent to the top thereof and having an outwardly bent end adapted to engage the outside of the bearing funnel and regulate the distance for the can spout.

Signed at Montreal, Canada, this 10th day of June, 1922.

OVIDE DUCHATELET.
